LATCH

William R. Bluehdorn, Hartford, Conn., and Forrest K. Howard, East Falls Church, Va.

Application March 15, 1937, Serial No. 130,964

2 Claims. (Cl. 285—146)

(Granted under the act of March 3, 1883, as amended April 30, 1928; 370 O. G. 757)

The invention described herewith may be manufactured and used by or for the Government for governmental purposes, without the payment to us of any royalty thereon.

This invention relates to a latch for threadedly connected members.

The purpose of the invention is to provide a simple and conveniently operable latch for maintaining the relative connected position of a pair of threaded members.

To these and other ends, the invention consists in the construction, arrangement and combination of elements described hereinafter and pointed out in the claims forming a part of this specification.

A practical embodiment of the invention is illustrated in the accompanying drawing, wherein:

Fig. 1 is a longitudinal sectional view of threaded members with the latch in locked position.

Fig. 2 is a similar view with the latch in unlocked position.

Fig. 3 is a plan view.

Fig. 4 is an end view.

Referring to the drawing by characters of reference there are shown a pair of cylindrical members 5 and 6 respectively having an externally threaded end 7 and an internally threaded end 8 whereby they are rotatably and separably connected.

In order to maintain a predetermined angular relation between the connected members, a latch carried externally by one member, in this instance the member 5, is arranged to have a locking engagement with the other member. The latch has its hub 9 positioned between apertured lugs 10—10 and extended through an opening 11 in the member 5. It is mounted on a pin 12 passing through the apertured lugs and, in order that the central portion of the pin may be positioned below the adjacent portion of the member 6, its ends are accommodated in a transversely disposed groove 13 in the member 5.

The short arm 14 of the latch is formed with a curved serrated face 15 adapted to engage a complementary curved serrated end face 16 on the member 6, which face is generally in a plane

perpendicular to the axis of said member. When the latch is in locking position the members 5 and 6 are incapable of rotational displacement. The offset position of the pin 12 with respect to the serrated faces 15 and 16 produces a camming action of the latch so that it will be necessary to apply force to the latch to move it out of locking position.

The latch includes a long actuating arm 17 having a bent extremity 18 which engages the member 5 when the latch is in locked position. A recess 19 is formed in the members 5 to facilitate grasping the tail of the arm 17 or to permit insertion of a member (not shown) for prying the latch upwardly.

We claim:

1. A pair of rotatably connectable members, the end of one of said members having a curved serrated face, the other member having an opening and a transverse groove in its outer surface extending on opposite sides of the opening, spaced lugs on said other member at opposite sides of the opening and having apertures coaxial with the groove, a pin passing through the apertures of the lugs and resting in the groove, a latch mounted on the pin between the lugs and partially disposed in the opening, a short arm on the latch having a curved serrated face for engaging the complementary face of said one member, and a long arm on the latch having a bent extremity for engaging the latch-supporting member when the latch is in locked position.

2. A pair of rotatably connectable members, one of said members being a latch-supporting member and the other an engaged member having a curved serrated face, spaced lugs on the latch-supporting member, a pin passing through the lugs and offset with respect to the engaged member, a latch disposed between the lugs and mounted on the pin, a short arm on the latch having a curved serrated face for engaging the complementary face of the engaged member, and a long actuating arm on the latch.

WILLIAM R. BLUEHDORN. 45
FORREST K. HOWARD.
